CLAIM

The ornamental design for a foldable child booster seat, as shown and described.

DESCRIPTION

1. Foldable child booster seat

1.1: Back

1.2: Perspective

1.3: Front

1.4: Top

1.5: Right

1.6: Left

1.7: Bottom

1.8: Front Folded

1.9: Right Folded

1.10: Perspective

1.11: Back Folded

1.12: Left Folded

1.13: Top Folded

1.14: Bottom Folded

The design is a child booster seat that can be mostly used in car; it can be folded into a smaller size; the armrest can be turned and then hidden in the pad.

The broken lines depict portions of the foldable child booster seat that form no part of the claimed design.
